FURNITURE-TIP

Application filed June 10, 1932. Serial No. 616,457.

This invention is an improved furniture-tip serving to prevent furniture from scratching and marring hardwood and other kinds of flooring and floor coverings. My object is to provide a protective device of this kind which will be efficient in operation, easy to apply, inexpensive to manufacture and attractive in appearance.

Generally speaking, my device comprises a small metal plate which is attachable to the end of the furniture leg and which may have any desired or preferred shape or outline but which will usually be a rounded plate or disc. This plate is provided at the periphery of its upper face with a channeled rim. This may be either a continuous or endless channeled rim or may be discontinuous and made up of individual sections. The rim may be and is preferably formed integrally with the plate for strength and convenience in manufacture. The device further comprises a floor protective pad made of any suitable material, preferably fibrous, such as any suitable fabric, felt, leather and the like. In practice I find that lamp-wicking is an excellent material for this pad. The pad covers the lower face of the metal plate or disc and has a peripheral portion which extends around the edge of the plate where it is received and clamped between the walls of the channeled rim.

The integral and continuous channeled-rim form of the device may be made by a stamping, swaging, spinning or other suitable metal-working operation; and is a preferred form of the device on account of its inherent strength as well as on account of the superior gripping strength of its walls on the protective pad.

The device is adapted to be nailed to the end of the furniture leg or the base of a chest, etc., with the floor protective pad exposed in order to contact with the floor. Preferably the nailing means for this purpose consists of an integral point or points struck up from the metal portion of the device, pref-

erably from the channeled rim. This rim is preferably inwardly channeled to conveniently receive and securely clamp the peripheral portion of the protective pad between its walls and at the same time permit the nailing points to extend upwardly from said rim for nailing the device to the article of furniture.

The invention will now be readily understood from the illustrative example shown in the accompanying drawing in which:

Fig. 1 is an elevation of the device shown attached in operative position to a chair leg or the like.

Fig. 2 is a vertical cross section partly in elevation on an enlarged scale of the parts shown in Fig. 1.

Fig. 3 is a perspective view from above of the metal portion of the device of the previous figures; and

Fig. 4 is the same of the protective pad portion of the device separate and apart from the metal portion of the device.

In the illustrated device, 10 designates a sufficiently stiff and strong metal disc or plate having at or towards the periphery of its upper face a channeled rim 12. This channeled rim is shown inwardly channeled and as being a continuous or endless rim formed integrally with the plate 10. The nailing points 14 are also shown integral with the metal portion of the device and as having been struck up from the channeled rim so as to project upwardly as shown, in position to be driven into the end of the furniture leg. The particular device illustrated has three of these nailing points 14 equally spaced in a circumferential series.

16 designates an adequately thick floor-protective pad, made preferably of lamp wicking, as heretofore stated, or of some other material suitable for the purpose, which will be sufficiently strong and durable and will not scratch or mar the floor, and which can be peripherally bent around the edge of the plate and securely clamped between the walls

of the channeled rim and is otherwise adapted to the practical manufacture of the device. The peripheral portion 16a of this pad extends around the edge of the disc or plate 5 and is received between the walls of the channeled rim 12 which are then forced towards each other, especially at their edge-adjacent portions, sufficiently to permanently grip and interlock with said peripheral portion 10 of the pad, whereby the protective pad is firmly secured to the metal portion of the device.

For illustrative purposes, this pad 16 is shown in Fig. 4 separately from the metal 15 portion of the device of Fig. 3. This Fig. 4 shows the pad with its peripheral portion 16a folded or bent up into the shape which it has when attached to the metal portion of the device. To take this shape, the flat piece of 20 pad material is peripherally notched, for example at four places 90° apart, thereby permitting the peripheral portions 16a thus formed to be folded upwardly and about the edge of the disc or plate for clamping between the walls of the channeled rim. The 25 lines or spaces 18 in Fig. 4 indicate where the sides of the described notches have come together due to the folding upwardly and inwardly of the peripheral portions of the pad. The pad material may be dyed to have a desirable color for improving appearance.

To attach the device, it is placed pad-side out against the end of the furniture-leg and the points 14 are then driven into the end of 35 the leg by hammering against the bottom of the device, especially against the peripheral zone in which the nail points are located.

While the device of this invention has been 40 described for purposes of illustration in considerable detail, it will be understood that other embodiments are possible and also that the scope of the invention is not limited to all the details of this disclosure but is to be 45 ascertained from the claims appended hereto in view of said disclosure and the prior art.

What I claim is:

1. A furniture-tip comprising a sheet-metal cup, the sides of which consist of an 50 annular U-sectioned channel having its walls and mouth extending radially outwardly, said cup having its bottom peripherally united with the rim of one of the walls of said channel; and a pad of floor-protective 55 material externally covering the bottom of the cup with the peripheral portion of said pad received into the annular channel clamped by and between its walls.

2. The furniture-tip claimed in claim 1, 60 further characterized by upwardly projecting nailing points integral with the afore- said channeled sides of the cup.

3. The furniture-tip claimed in claim 1, 65 further characterized by nailing points springing integrally from the innermost por-

tion of the aforesaid channeled sides of the cup and projecting upwardly therefrom with their pointed ends above the mouth level of the cup.

4. The furniture-tip claimed in claim 1 70 further characterized by means for fastening said cup to the article of furniture with its channeled sides extending upwardly.

In testimony that I claim the foregoing, I have hereunto set my hand this 7th day 75 of June, 1932.
